UNITED STATES PATENT OFFICE.

SOPHIA BLICKMAN, OF NEW YORK, N. Y.

DESIGN FOR A STERILIZER.

43,689.

Specification for Design.

Patented Mar. 11, 1913.

Application filed May 1, 1912. Serial No. 694,584. Term of patent 14 years.

To all whom it may concern:

Be it known that I, SOPHIA BLICKMAN, a subject of the Czar of Russia, residing in the borough of Manhattan, city of New York, county and State of New York, have invented a new, original, and ornamental Design for Sterilizers, of which the following is a specification, reference being had to the accompanying drawings, forming part thereof.

Figure 1 of the drawings is a front elevation, Fig. 2 is a side elevation and Fig. 3 is a top plan view of a sterilizer showing my new design.

I claim:

The ornamental design for a sterilizer as shown.

In testimony whereof, I have hereunto set my hand in the presence of the two subscribing witnesses.

SOPHIA BLICKMAN.

Witnesses:

HARRY PICKETT,
MANUEL BLICKMAN.
